United States Patent Office.

CHARLES P. WHITMAN, OF CHARLEMONT, MASSACHUSETTS, ASSIGNOR TO HIMSELF AND W. C. DODGE, OF WASHINGTON, DISTRICT OF COLUMBIA.

Letters Patent No. 97,010, dated November 16, 1869.

IMPROVEMENT IN BIT-STOCK FASTENING.

The Schedule referred to in these Letters Patent and making part of the same.

To all persons to whom these presents shall come:

Be it known that I, CHARLES P. WHITMAN, of Charlemont, of the county of Franklin, and State of Massachusetts, have invented a new and useful Bit-Stock Fastening; and do hereby declare the same to be fully described in the following specification, and represented in the accompanying drawings, of which—

Figure 1 is a side view of a bit-stock provided with my invention.

Figures 2 and 3 are longitudinal sections of the fastening, they being taken at right angles to each other.

Figure 4 is an end view of the fastening.

Figure 5 is a side view of the stock, as it appears without the cylindrical or tubular screw-nut.

Figure 6 is a longitudinal section of the screw-nut.

The object of my invention is to produce a bit-stock into which bits, as ordinarily made, can be inserted, without fitting them especially therefor, as has generally to be done, and which shall hold them firmly, and shall centre them by the simple act of fastening them in.

To do this, I construct the lower end of the stock A, with a pyramidal recess or socket, *a*, of such a size as to permit the tapering end of the shank *h* of the bit to be inserted, as shown in figs. 2 and 3.

This recess or socket should be of such a size that the smallest end of the largest shank may be inserted far enough to hold it and prevent it from turning therein, and, at the same time, receive the smallest shank, and prevent it from turning also. As bits are usually made with their shanks varying but little in size, this can be readily accomplished.

Upon the outside of this end of the stock A, I cut or form a screw-thread, *b*, as represented in fig. 5, this thread extending for some distance along the stock.

I then provide a cup-shaped ferrule or cap, *B*, having a corresponding screw-thread formed on its interior surface, this cap being of such a size as to fit easily on to the end of the stock, and screw thereon for an inch or two.

In the centre of the outer or closed end of this cap *B*, I make a circular opening, *d*, large enough to receive the rounded stem of the bit below the shoulders of the shank *h*, this hole *d* being more clearly shown in fig. 4.

From this central hole *d*, I make a lateral opening, *e*, which extends outward to the outside of the cap, and extending a little way down on one side, where it

is increased in size sufficiently to permit the shank *h* of the bit to be inserted through it into the socket *a*, in the end of the stock A.

The hole *d*, I make conical, its greatest diameter being inside of the cap, so that when the bit is inserted and the cap *B* is screwed on to the stock A, this conical portion will bear upon the rounded shoulders of the shank *h*, and thereby crowd the stem of the bit to the centre of the cap, thus centring of the bit truly in the stock.

The shoulder of the cap which surrounds the opening *d*, as the cap is screwed up, engages over the shoulders of the shank *h*, thereby crowding the shank *h* into the socket *a*, and thus holds the bit firmly in the stock.

To remove the bit, it is only necessary to loosen the cap, by partially unscrewing it, when the bit can be taken out, and another inserted.

By these means I am able to produce a bit-stock that will receive, centre, and securely hold any ordinary bit, as made by the manufacturer, without any special fitting of the bit.

I am aware that a bit-stock has been previously made, in which a cap was used to hold the bit in the stock, but said cap had to be entirely detached, to insert or remove the bit, and was secured to the stock by means of a sectional screw-thread cut on a narrow projection on one side of the stock, which was far more difficult and expensive to make.

Having thus described my invention,

What I claim, is—

1. A bit-stock, having a socket, *a*, formed in its end, to receive the shank of the bit, with a screw-thread formed on its exterior, and a cap, *B*, with a corresponding internal screw-thread, with the openings *d* *e* formed in it, substantially as described.

2. The cap *B*, having a circular opening in its end, of such a size as to receive the stem of the bit, but not large enough to permit the shoulders of the shank to pass through it, said opening being connected, by lateral passage, with an opening in the side of the cap, of sufficient size to permit the shank of the bit to be inserted therein, substantially as described.

CHARLES P. WHITMAN.
